AURIN M. CHASE, OF SYRACUSE, NEW YORK.

INTERNAL-COMBUSTION ENGINE.

1,051,986.

Specification of Letters Patent.

Patented Feb. 4, 1913.

Application filed July 27, 1911. Serial No. 640,740.

To all whom it may concern:

Be it known that I, AURIN M. CHASE, of Syracuse, in the county of Onondaga and State of New York, have invented a new and useful Internal-Combustion Engine, of which the following is a specification.

This invention relates to internal combustion engines and has for its object the production of a particularly simple and efficient construction whereby the portion of the piston movable in the hottest zone of the cylinder is spaced apart from the inner face of the walls of the cylinder and requires substantially no lubrication, and whereby gas and carbon deposits are prevented from entering between such portion of the piston and the opposing inner face of the walls of the cylinder; and the invention consists in the combinations and constructions hereinafter set forth and claimed.

In describing this invention, reference is had to the accompanying drawing which is a vertical sectional view of the cylinder of my engine, and the piston movable therein, the remaining parts of the engine being omitted.

1 is the cylinder and 2 the piston movable therein, the piston having at one end an extension 3 which is movable in the hottest zone of the cylinder, and is of slightly less diameter than the contiguous portion of the inner face of the cylinder and of slightly less diameter than the body or trunk portion 4 of the piston, which trunk portion is movable in the cooler zone of the cylinder, engages the inner face of the walls of the outer end portion of the cylinder and is provided substantially centrally between its ends with the usual connecting means, as a pivot pin *a*, for a link or pitman transmitting power from, and to, the piston, such extension being provided with suitable means for rendering the extension gas tight without receiving any of the strain due to guiding and resisting the lateral strain or thrust upon the piston in its movement.

In the illustrated embodiment of my invention, such means consists of an ordinary piston ring or rings 5 located near the upper or inner end of the extension 3 and spaced apart from the base of the extension, such piston ring or rings 5 being of sufficient resiliency to merely engage the walls of the cylinder lightly. As the piston rings 5 do not assist in guiding and resisting the lateral thrust upon the piston in its reciprocating

movement they require practically no lubrication. The piston is guided in its reciprocating movement by the trunk or body portion 4 thereof, which may, if desired, be provided with piston rings 6.

Owing to the construction set forth, the head or extension 3 of the piston which runs in the hottest zone of the piston chamber requires substantially no lubrication, as a space 7 intervenes between the periphery of such extension and the walls of the cylinder and the gas or motive fluid is prevented by the piston rings 5 from following down along the periphery of the extension and depositing carbon or other matter tending to foul the cylinder.

The use of means for rendering the extension gas tight is particularly advantageous in two-cycle engines as such means prevents the motive fluid from escaping through the exhaust 8, along the extension as the piston is rising, and also prevents the exploded charge from passing out through the exhaust 8 before the head of the piston uncovers the exhaust; and said means is particularly advantageous in engines of the four cycle type for the reason that it prevents the accumulation of carbon deposit in the space between the extension and the walls of the cylinder.

What I claim is:

1. In an internal combustion engine, a cylinder, and a piston movable in the cylinder, the piston being formed with a head having its periphery located close to, and disengaged from, the inner face of the cylinder, the portion of the piston in rear of said head being of greater diameter than the same and directly engaging the inner face of the cylinder for guiding the piston in its movement, said head being provided with a piston ring engaging the inner face of the cylinder and arranged in advance of, and spaced apart from, said portion of the piston in rear of said head, substantially as described.

2. In an internal combustion engine, a cylinder, and a piston movable in the cylinder, the main body of the piston being of substantially the same diameter as the contiguous portion of the inner face of the cylinder, the main body directly engaging said face and guiding the piston in its movement, the piston having an extension at one end forming the head of the piston, said extension being of less diameter than the con-

- tiguous portion of the inner face of the cylinder for causing a space to intervene in advance of said main body between the periphery of the extension and the inner face 5 of the cylinder, and means near the end face of the extension for directly engaging the inner face of the cylinder and rendering the advance end of said space substantially gas-tight, substantially as described.
- 10 3. In an internal combustion engine, a cylinder, and a piston movable in the cylinder, the advance end of the piston being movable in the hottest zone of the cylinder and having its periphery running close to, 15 and spaced apart from, the inner face of the cylinder, and means provided on said advance end and spaced apart from the base of said end for preventing gas from entering the space between said end and the inner face of the cylinder, the rear end of the piston being movable in the cooler zone of the cylinder and formed of greater diameter than said advance end and directly engaging the inner face of the cylinder and guiding 20 the piston, substantially as described.
- 25 4. In an internal combustion engine, a cylinder, and a piston movable in the cylinder, the main body of the piston being mov-

able in the cooler zone of the cylinder and being of substantially the same diameter as 30 the contiguous portion of the inner face of the cylinder and being provided with connecting means arranged substantially centrally between its ends, the piston having an extension projecting in advance of one end 35 of said main body and forming the head of the piston, the extension being movable in the hottest zone of the cylinder, and being of less diameter than the contiguous portion of the inner face of the cylinder for 40 causing a space to intervene in advance of said main body between the periphery of the extension and the inner face of the cylinder, and means near the advance end of the extension for directly engaging the inner face 45 of the cylinder and rendering the advance end of said space substantially gas-tight.

In testimony whereof, I have hereunto signed my name in the presence of two attesting witnesses, at Syracuse, in the county 50 of Onondaga, in the State of New York, this 24th day of July, 1911.

AURIN M. CHASE.
